UNITED STATES PATENT OFFICE

170,752

PORCH COLUMN

Winford L. Enghauser, Cincinnati, Ohio

Application April 15, 1953, Serial No. 24,525

Term of patent 14 years

(Cl. D54—2)

To all whom it may concern:

Be it known that I, Winford L. Enghauser, a citizen of the United States, residing at Cincinnati, in the county of Hamilton and State of Ohio, have invented a new, original, and ornamental Design for a Porch Column, of which the following is a specification, reference being had to the accompanying drawing, forming a part thereof.

Figure 1 is a front elevational view of the porch column, showing my new design.

Figure 2 is a side elevational view thereof.

I claim:

The ornamental design for a porch column, substantially as shown.

WINFORD L. ENGHAUSER.
